United States Patent Office

Des. 191,833
Patented Nov. 28, 1961

191,833

SLED

Benjamin F. Brasch, 5207 Orchard Park Drive, Parma,
Ohio, and George S. Mountford, 2650 Dover Center
Road, Westlake, Ohio

Filed July 25, 1961, Ser. No. 66,150

Term of patent 14 years

(Cl. D34—15)

FIG. 2

FIG. 1

FIG. 1 is a top plan view of a sled showing our new design;

FIG. 2 is a bottom plan view of the sled;

FIG. 3 is a perspective view of the sled;

FIG. 4 is a side elevation of the sled, the other side being substantially the same in appearance as the side shown, and

FIG. 5 is a rear elevation of the sled.

We claim:

The ornamental design for a sled, as shown and described.
